United States Patent Office

Des. 184,265
Patented Jan. 13, 1959

184,265

TACKER OR SIMILAR ARTICLE

Henry Ruskin, Bayside, N. Y., assignor to Swingline, Inc.,
Long Island City, N. Y., a corporation of New York

Application February 10, 1958, Serial No. 49,578

Term of patent 14 years

(Cl. D74—1)

Des. 184,265

PAGE 2

FIG - 2

FIG - 4

Fig. 1 is a side perspective view of a tacker showing my new design;

Fig. 2 is a top plan view thereof as it appears with the handle in lowered position;

Fig. 3 is a side elevational view thereof showing the handle in lowered position and locked in place;

Fig. 4 is a bottom plan view; and

Fig. 5 is a perspective view of the side opposite to that of Fig. 1 as it appears with the handle in raised position.

I claim:

The ornamental design for a tacker or similar article, as shown.
